DEFINITE TIME RELAY

Filed Oct. 18, 1934

UNITED STATES PATENT OFFICE

2,037,572

DEFINITE TIME RELAY

Robert W. Goff, Schenectady, N. Y., assignor to
General Electric Company, a corporation of
New York

Application October 13, 1934, Serial No. 748,839

11 Claims. (Cl. 175—375)

My invention relates to relays, more particularly to relays of the definite time, motor driven type, and has for an object the provision of an inexpensive and reliable definite time relay.

Various time delay relays have heretofore been proposed to operate with a more or less definite time delay through the agency of dashpots or similar devices. Arrangements of this type have been found to be somewhat uncertain in their action and to be rather unsatisfactory because of the difficulty which arises in accurately adjusting the time setting. Definite time relays have also been proposed in which the time delay is accomplished by means of a timing motor associated with contact operating mechanism arranged to be actuated upon a predetermined rotation of the motor. One objection to previously known relays of this latter type is that the timing motor is usually designed to operate at a standard voltage and the relay can therefore be used only in connection with a source of voltage of the proper value. Accordingly, it is a further object of my invention to provide an inexpensive and easily adjustable definite time relay of the motor driven type which may be applied in circuits of widely differing voltages and which employs a standard voltage timing motor.

In carrying out my invention in one form I provide a contact member and a latch for normally holding the contact member in a predetermined biased position together with an electric motor and time adjustable operating mechanism driven by the motor for releasing the latch. This operating mechanism between the motor and the latch is normally supported out of driving relationship with the motor, a solenoid being provided for moving it into driving relationship. This movement also applies a second relatively strong biasing force to the contact member so that when the latch is moved by the operating mechanism to release the contact member the contact member moves to a second predetermined position.

When the solenoid is deenergized, the operating mechanism moves in accordance with its bias out of driving relation with the motor and by means of suitable springs the various parts of the operating mechanism are returned to their initial positions. Also the spring bias applied to the contact member upon movement of the operating mechanism into driving position is removed, and the contact member is thereupon returned to its former position by its relatively weak biasing spring and secured in that position by the latch.

The operating solenoid has the further pur-

pose of serving as an auto transformer for energizing the motor, the solenoid being provided with an intermediate voltage tap giving the desired voltage for the motor when the solenoid is connected to a supply source of predetermined voltage. This arrangement has the advantage that by supplying a solenoid coil having a suitable voltage tap the relay can be adapted within reasonable voltage limits for the voltage of the supply source available. The motor may therefore be standard for all voltages, the relay being adapted for the particular voltage by selecting a suitable relatively inexpensive solenoid coil.

For a more complete understanding of my invention, reference should now be had to the accompanying drawing in which Fig. 1 is a front view of a relay embodying my invention; Fig. 2 is a side view thereof, partly in section, along line 2—2 of Fig. 1; Fig. 3 is a somewhat diagrammatic view of my relay in perspective; and Fig. 4 is a view in exploded perspective of the timing shaft and the mechanism carried thereby for adjusting the time setting of the relay and for tripping the latch.

In the preferred embodiment of my invention illustrated I have shown a relay comprising a contact carrying member 1 pivotally mounted for movement between two circuit controlling positions on a fixed pin 2 supported by a bracket 3 fastened to an insulating base plate 4. A torsion spring 5 surrounding the pivot pin 2 and having its ends fastened respectively to the pin and to the contact carrying member 1 serves to bias the contact carrying member to one of its two circuit controlling positions, in which position the contact carrying member 1 normally is retained by means of a notch 6 formed in the pivoted latch finger 7. The latch finger 7 is mounted on a pivot pin 8 carried by the bracket 3 and is normally biased to latching position by a spring 9. Carried by the movable contact member 1 is a normally ineffective second biasing means, the operation of which will be more fully described later, comprising a headed pin 10 freely slideable through a journal 11 and carrying a normally unstressed spring member 12 the ends of which respectively bear against the contact carrying member 1 and the head of the pin 10.

For operating the contact carrying member 1 with the desired definite time delay, I provide a constant speed timing motor 13, preferably of the self-excited synchronous type, arranged to rotate a driving member or gear 14 through suitable speed reduction mechanism contained in the housing 15. Adjacent the gear 14 is a driven

member or gear 17 normally supported out of driving relation with the motor driven gear 14 on a timing shaft 18 journaled in supporting ears 19 on a tiltable arm 16. In order that the arm 16 may be tilted so as to bring the gear 17 into driving relation with the gear 14 the arm 16 is supported on a beam 20 which is mounted for rotary movement on brackets 21 and 22 fastened to the base plate 4 and which is arranged to be moved by a solenoid comprising a magnetic frame 23, a winding 24 and a movable plunger 25 pivotally connected to a finger 26 extending from the beam 20.

Carried by the timing shaft 18, is the time adjusting and contact operating mechanism which comprises a timing arm 27 provided with an operating finger 28 and a stop finger 29, a time adjusting or calibrating disk 30 having a plurality of slots 31 spaced about the periphery thereof and provided with an extending portion 32 disposed in the path of the operating finger 28, and a tripping arm 33 shaped to provide an outwardly extending finger 34 and a pair of downwardly extending legs 35 and 36. As shown best in Figs. 3 and 4, the time adjusting and contact operating mechanism is assembled on the timing shaft 18 with the timing arm 27 keyed to the shaft by means of a pin 37 for rotation therewith, and with the calibrating disk 30 and the tripping arm 33 arranged for rotation with respect to the timing shaft 18 on a bearing member 38. In order to hold the three operating elements 27, 30 and 33 in face-to-face engagement on the shaft 18, a spring washer 39 is provided and the whole assembly is positioned on the shaft 18 by means of a nut 40 which cooperates with the threaded end 41 of the shaft 18. In addition to the above elements, the time adjusting means includes a locking spring 42, one end of which is fastened to the tripping arm 33, as by rivets 43, and the other end of which is provided with a detent finger 44 for selectively engaging one of the slots 31 arranged about the periphery of the calibrating disk 30. In order to bias the timing arm 27 and the tripping arm 33 to their respective initial positions, a coil spring 45 is provided having its ends respectively fastened to the ear 19 and to the timing arm 27 to hold stop finger 29 normally against a shoulder 46 on the tiltable arm 16, and a spring finger 47 is fastened to the beam 20 with its free end bearing against the leg 35 on the tripping arm 33 to hold the leg 36 of the tripping arm in contact with a stop finger 48 extending from the tiltable arm 16.

Various relays heretofore known in the art have been provided with a tripping arm and a timing arm arranged to cooperate to actuate a contact carrying member, in which relays the time setting has been varied by changing the initial relative positions of the timing arm and the tripping arm. In my relay, however, the time setting of the relay is varied without altering the initial position of either the timing arm or the tripping arm by simply varying the position of the interposed finger 32 relative to the two initial positions of the arms. In other words, to vary the time setting of my relay, it is necessary only to bend the locking spring 42 outwardly away from the calibrating disk 30 so that the detent 44 is free of the notches 31 and then to rotate the calibrating disk 30 until a slot which corresponds to the desired time interval is aligned with the detent 44. The spring finger 42 is then released and the detent 44 cooperates with the aligned slot 31 to lock the interposed finger 32 in

a position relative to the initial positions of the timing arm and the tripping arm which corresponds to the desired time interval. For the purpose of assisting in selecting the desired slot on the periphery of the calibrating disk 30, a pointer 33a is provided on the tripping arm 33 and the adjacent face of the dial 30 may be provided with suitable indicia so that when the detent finger 44 is in alignment with a slot corresponding to say a 25 second interval, a numeral 25 on the face of the calibrating disk will be opposite the pointer 33a.

As will be seen upon reference to Fig. 3, the operating solenoid 24 is connected to the supply leads 101 and 102 for energization from a suitable source of alternating current through a conventional pushbutton station comprising a "start" button and a "stop" button. An interlock contactor comprising the fixed contacts 49 and 50 and a bridging member 51, resiliently mounted on a finger 52 carried by the beam 20, is arranged to bypass the "start" button when the solenoid is energized in order that the relay, when once the "start" button has been pushed, will remain energized until its complete cycle of operation has taken place and can be reset only by actuating the "stop" button. In order that standard rated voltage may be supplied to the timing motor 13, circuit connections comprising conductors 53 and 54 are provided for connecting the motor 13 to an intermediate voltage tap 55 on the solenoid winding 24. Assuming that it is desired to operate the relay from a 440-volt circuit and that the motor 13 is designed for operation at 110 volts, the intermediate tap 55 would be so located relative to the ends of the winding 24 as to supply 110 volts to the timing motor. It will be obvious that with such an arrangement a relay provided with a 110 volt motor may be adapted for operation upon a circuit having a voltage of 220 volts, 440 volts or 660 volts, by simply supplying a properly wound solenoid having a proper intermediate voltage tap. Arranged in the motor supply conductor 54 is a normally closed switch comprising the fixed contacts 56 and 57 and a spring pressed bridging member 58 which is arranged to be operated by the finger 59 carried by the movable contact member 1 to deenergize the motor when the movable contact member is actuated from its latched position to its other circuit controlling position.

When the solenoid 24 is energized to attract its plunger 25 and thus rotate the beam 20, the tiltable arm 16 is moved to bring gears 14 and 17 into mesh with each other and to bring the tripping member 33 into tripping position directly below the latch finger 7. Movement of the tiltable arm 16 is also effective by means of finger 60 extending therefrom, to urge the headed pin 10 through its journal 11 so as to compress the spring 12 and apply to the movable contact carrying member 1 a biasing force which opposes the normal biasing force exerted by the spring 5 and which tends to move the contact carrying member 1 from its latched position.

Although any suitable contact arrangement may be provided for operation by the movement of the contact carrying member 1, I prefer to provide a pair of normally closed contacts 61 and 62 and a pair of normally open contacts 63 and 64 arranged to operate as a single pole, double throw switch in which the movable contacts 61 and 63 are electrically connected to a common terminal 65 and resiliently supported on the contact carrying member 1 by a leaf spring 66.

It is believed that a complete understanding of my invention may now be had from a description of the operation of my relay without reference to the circuit to be controlled. Various applications of my relay will occur to those skilled in the art and no claim is here made to any particular circuit. With the "start" button in open circuit position and the various elements of the relay in the normal positions shown in the drawing, the time setting of the relay may be adjusted to the desired value in the manner hereinbefore described, and the "start" button then actuated to energize the solenoid winding 24 and the timing motor 13. Energization of the solenoid winding and the consequent movement of the solenoid plunger 25 rotates the beam 20 about its axis to close the interlock contacts 49 and 50 and to tilt the arm 16, bringing the contact operating and time adjusting mechanism into driving relationship with the motor 13. More specifically when the arm 16 is tilted, the gears 17 and 14 are brought into mesh with each other, the trip finger 34 is moved to a position immediately below the latch 7, and the slidable pin 10 is moved 25 through its journal 11 to compress the spring 12 and apply to the contact carrying member 1 a biasing force which is greater than and opposed to the normal biasing force exerted by the spring 5. The motor 13 is now rotating at synchronous speed and through the reduction gearing contained in the housing 15, the gears 14 and 17 and the timing shaft 18, rotates the timing arm 27 from its initial position against the bias of the spring 45.

When the timing arm 27 has rotated sufficiently to bring the operating finger 28 into contact with the interposed finger 32 carried by the disk 30, continued movement of the arm 27 will cause the disk 30 to rotate and the locking spring 42 will transmit this rotation of the disk 30 to the tripping member 33 and move the tripping member against the bias of the spring 47. As the tripping member 33 rotates, the trip finger 34 carried thereby will move upward and raise the latch finger 7 to release the contact carrying member 1. When the latch 7 has been raised sufficiently to permit the contact carrying member to clear the notch 6, the force exerted by the biasing spring 12 moves the contact carrying member 1 from its normal latched position to open the contacts 61 and 62 and to close the contacts 63 and 64. As the contact carrying member 1 moves from its normal position, the finger 59 actuates the bridging member 58 away from the fixed contacts 56 and 57 to deenergize the motor 13.

The relay has now completed its cycle and will remain in its operated position until the "stop" button is actuated to deenergize the solenoid 24. Actuation of the "stop" button serves to automatically reset the relay. It will be noted from Figs. 2 and 3 that the timing shaft 18 and its associated time adjusting and tripping mechanism are mounted off center with respect to the tiltable arm 16, and therefore will act as a gravity biasing means to return the arm 16 to its normal position upon deenergization of the solenoid 24. When the "stop" button is actuated, therefore, the solenoid 24 is deenergized, the interlock contacts 49 and 50 are opened, and the arm 16 returns to its normal position, disengaging the gears 14 and 17, which allows the timing arm 27 and the tripping member 33 to be returned to initial position by their respective biasing springs 45 and 47, and releasing the spring 12, which

allows the contact carrying member 1 to be returned to its normal latched position by the biasing spring 5. The relay now is in its normal reset position and the above cycle may again be initiated by actuating the "start" button. 5

While I have shown a particular embodiment of my invention, it will be understood, of course, that I do not wish to be limited thereto since many modifications may be made, and I, therefore, contemplate by the appended claims to 10 cover any such modifications as fall within the true spirit and scope of my invention.

What I claim as new and desire to secure by Letters Patent of the United States is:

1. A definite time relay comprising a motor, 15 a contact member, means driven by said motor for operating said contact member a definite time after energization of said motor, said motor and said operating means being normally out of driving relationship, a solenoid for establishing a 20 driving relationship between said operating means and said motor when said solenoid is energized, a tap in said solenoid coil, and circuit connections including said tap for connecting said motor to said solenoid. 25

2. A definite time relay comprising a driving member and a driven member normally disposed in disengaged relationship with each other, means including a solenoid for moving said members into driving relationship when said solenoid 30 is energized, means for tapping off an intermediate voltage from said solenoid, a motor arranged to rotate said driving member, circuit connections for energizing said motor in accordance with said intermediate voltage, circuit controlling 35 relay contacts, and means responsive to a predetermined rotation of said driven member for operating said contacts.

3. A definite time relay comprising a constant speed timing motor, circuit controlling contacts, 40 means driven by said motor for operating said contacts a definite time after energization of said motor, said motor and said means being normally out of driving relationship with each other, a solenoid provided with a plunger for actuating 45 said means into driving relationship with said motor when said solenoid is energized, an intermediate tap on said solenoid, circuit connections including said tap for energizing said motor in accordance with the voltage across a portion 50 of said solenoid to drive said contact operating means and means controlled by the operation of said contacts for deenergizing said motor. 55

4. A definite time relay comprising a contact carrying member, means for normally biasing said member to one of two positions, a latch for retaining said member in said biased position, time delay means including a timing motor and a pair of normally disengaged gears, a solenoid 60 for moving said gears into driving relationship, means responsive to a predetermined rotation of said gears for tripping said latch and a second biasing means arranged to be rendered effective by movement of said gears into driving relationship for urging said contact carrying member from its latched position in opposition to said normal biasing means whereby said member is moved to said other position when said latch is tripped. 65

5. A definite time relay comprising a contact carrying member, means for normally biasing said member to one of two positions, a latch for retaining said member in said biased position, a timing motor provided with a driving member, 70

2. timing shaft carrying a driven member normally disengaged from said driving member, a tiltable arm for supporting said timing shaft and said driven member in said disengaged position, means for tilting said arm to engage said driving and driven members, means carried by said shaft for tripping said latch upon a predetermined rotation of said driving and driven members, and means actuated by the tilting of said arm for oppositely biasing said contact carrying member to overcome said normal biasing means whereby said contact carrying member is moved to said other position when said latch is tripped.
3. A definite time relay comprising a contact carrying member, means for normally biasing said member to one of two positions, a latch for retaining said member in said biased position, a timing motor provided with a driving member, a timing shaft carrying a driven member normally disengaged from said driving member, a tiltable arm for supporting said timing shaft and said driven member in said disengaged position, a solenoid for tilting said arm to engage said driving and driven members, circuit connections for energizing said timing motor in accordance with the voltage across a portion of said solenoid to rotate said driving and driven members, means carried by said shaft for tripping said latch upon a predetermined rotation of said driving and driven members, and means actuated by the tilting of said arm for oppositely biasing said contact carrying member to overcome said normal biasing means whereby said member is moved to said other position when said latch is tripped.
4. The combination with a definite time relay having a rotatable timing arm, a latched contact carrying member and a tripping member for releasing said latch, said timing arm and said trip member being respectively biased to initial position, of means for actuating said tripping member upon a predetermined rotation of said timing arm comprising a disk rotatably mounted with respect to said timing arm and to said tripping member having a plurality of slots arranged about the periphery thereof, means on said disk interposed in the path of said timing arm to move said disk upon a predetermined rotation of said arm from its initial position, and means for engaging said tripping member with said disk to move said tripping member with said timing arm, said engaging means comprising a spring finger carried by said tripping member and adapted to cooperate with a selected one of said slots on said disk to lock said interposed means in a selected position relative to said timing arm thereby to vary the time setting of said relay.
5. The combination with a definite time relay having a timing arm, a latched contact carrying member and a tripping arm for releasing said latch, said timing arm and said tripping arm being respectively biased to initial position, of means for actuating said tripping arm upon a predetermined rotation of said timing arm comprising a disk rotatably mounted with respect to said arms having a plurality of slots about the periphery thereof, means on said disk interposed in the path of one of said arms, and means carried by the other of said arms for engaging a selected slot in said disk to lock said interposed means in a selected position relative to the initial positions of said arms thereby to vary the time setting of said relay.
6. The combination with a definite time relay having a contact carrying member, a timing arm, an actuating member for moving said contact carrying member, said arm and said actuating member being normally biased to respective initial positions and means for rotating said arm from said initial position, of adjustable means for operating said actuating member upon a predetermined rotation of said timing arm comprising a disk rotatably mounted with respect to said arm and said actuating member having a plurality of slots about the periphery thereof, means on said disk interposed in the path of said timing arm, and means carried by said actuating member for engaging a selected slot in said disk to lock said interposed means in a selected position relative to said initial positions of said timing arm and said actuating member thereby to vary the time setting of said relay.
7. The combination with a definite time relay having a contact carrying member, a timing arm, an actuating member for moving said contact carrying member, said timing arm and said actuating member being normally biased to respective initial positions, and means for rotating said arm from said initial position, of adjustable means for operating said actuating member upon a predetermined rotation of said timing arm comprising means interposed in the path of said timing arm and rotatably mounted with respect to said arm and said actuating member, and means carried by said actuating member for locking said interposed means in a selected position relative to said initial positions of said timing arm and said actuating member thereby to vary the time setting of said relay.
8. The combination with a definite time relay having a timing arm, a latched contact carrying member and a tripping arm for releasing said latch, said timing arm and said tripping arm being respectively biased to initial position, of means for actuating said tripping arm upon a predetermined rotation of said timing arm comprising a disk rotatably mounted with respect to said arms having a plurality of slots about the periphery thereof, means on said disk interposed in the path of one of said arms, and means carried by the other of said arms for engaging a selected slot in said disk to lock said interposed means in a selected position relative to the initial positions of said arms thereby to vary the time setting of said relay.
9. The combination with a definite time relay having a contact carrying member, a timing arm, an actuating member for moving said contact carrying member, said arm and said actuating member being normally biased to respective initial positions and means for rotating said arm from said initial position, of adjustable means for operating said actuating member upon a predetermined rotation of said timing arm comprising a disk rotatably mounted with respect to said arm and said actuating member having a plurality of slots about the periphery thereof, means on said disk interposed in the path of said timing arm, and means carried by said actuating member for engaging a selected slot in said disk to lock said interposed means in a selected position relative to said initial positions of said timing arm and said actuating member thereby to vary the time setting of said relay.
10. The combination with a definite time relay having a contact carrying member, a timing arm, an actuating member for moving said contact carrying member, said timing arm and said actuating member being normally biased to respective initial positions, and means for rotating said arm from said initial position, of adjustable means for operating said actuating member upon a predetermined rotation of said timing arm comprising means interposed in the path of said timing arm and rotatably mounted with respect to said arm and said actuating member, and means carried by said actuating member for locking said interposed means in a selected position relative to said initial positions of said timing arm and said actuating member thereby to vary the time setting of said relay.
11. A definite time relay comprising a contact carrying member, means for normally biasing said member to one of two positions, a latch for retaining said member in said biased position, a timing motor provided with a driving gear, a timing shaft carrying a driven gear normally disengaged from said driving gear, a tiltable arm for supporting said timing shaft and said driven gear in said disengaged position, a solenoid for tilting said arm to engage said gears, circuit connections for energizing said timing motor in accordance with the voltage across a portion of said solenoid to rotate said gears, means actuated by the tilting of said arm when said solenoid is energized for oppositely biasing said contact carrying member to overcome said normal biasing means whereby said member will be moved to said other position when said latch is tripped, a timing arm mounted on said timing shaft for rotation with said gears and biased to an initial position, means rotatably mounted on said shaft for tripping said latch, said tripping means being normally biased to an initial position, a disk mounted for rotation relative to said timing arm and to said tripping means having a plurality of slots arranged around the periphery thereof, means on said disk interposed in the path of said timing arm, and means extending from said tripping means for engaging a selected one of said slots to lock said interposed means in a selected position relative to said initial positions of said tripping means and said timing arm to thereby vary the time setting of said relay.

ROBERT W. GOFF.
